UNITED STATES PATENT OFFICE.

WILLIAM DEMUTH, OF NEW YORK, N. Y.

DESIGN FOR A PIPE MOUTH-PIECE.

SPECIFICATION forming part of Design No. 13,029, dated July 11, 1882.

Application filed May 24, 1882. Term of patent 7 years.

To all whom it may concern:

Be it known that I, WILLIAM DEMUTH, a citizen of the United States, residing at New York, in the county and State of New York, have invented and produced a new and original Design for the Mouth-Piece of a Smoking-Pipe, of which the following is a specification.

This design consists in a sharp-pointed peak projecting from the back of an angular mouth-piece.

The accompanying drawing represents a side view of my design.

In this drawing, the letter A designates an angular mouth-piece, the inner line of which is concave, while from its outer line or back extends a sharp-pointed peak, B, which imparts

to my mouth-piece a novel and ornamental appearance.

What I claim as new, and desire to secure by Letters Patent, is—

The design for the mouth-piece of a smoking-pipe, consisting of a sharp-pointed peak projecting from the back of the angular mouth-piece, as shown and described.

In testimony whereof I have hereunto set my hand and seal in the presence of two subscribing witnesses.

WM. DEMUTH. [L. S.]
